UNITED STATES PATENT OFFICE.

HANS ALBERT FRIEDRICH LEOPOLD MAX WARSCHAU, OF HAMBURG, GERMANY.

ENGINE OR PUMP.

Application filed February 5, 1926, Serial No. 86,335, and in Germany February 7, 1925.

In the U. S. Patent 1,150,430 (Ser. No. 853,781) a rotary machine is illustrated and described which is adapted to operate as an engine or pump and wherein a rotary and oscillatory piston is formed by an intermediate disc. This disc, up to the inlet and outlet slots or ports controlled by an annular casing, is supplemented by a sphere, the said intermediate disc being linked by a universal joint, to two rotating spherical sectors inclined to one another and connected by the axes at the slots.

Extensive experiments with such devices have led to the conclusion that, especially when the forcing or delivery means is a fluid, the efficiency of the device does not fulfil the requirements of practical commercial use, and this is because the spaces, shortly before the final closing of the inlet and outlet slots, are still comparatively large between the corresponding faces of the intermediate disc and the inner faces of the spherical shell. The consequence is, that water, for example, to be pumped, is held back in the said spaces shortly before the outlet slots are closed and is therefore forced with great pressure through a comparatively small orifice, thus creating losses by friction which materially reduces the efficiency. Such losses are likewise present upon the admission to the inlet opening when their opening movement commences.

These disadvantages are avoided by this invention in which the walls of the shell which may be said to supplement the intermediate disc by a hollow sphere, are so thickened that the spherical sectors assume the shape of wedges, the breadth of which do not exceed, or only slightly exceed, the width of the ports. Thus the spaces which are to be filled or emptied, shortly before the closing of the inlet and outlet slots, are considerably reduced, and the efficiency of the device greatly increased.

In the drawing two forms of construction of the invention are illustrated, the connection of the spherical sectors with the intermediate disc being shown for the sake of simplicity, as a simple wedge guide.

Fig. 1 is a vertical central section of the device.

Fig. 2 is a section on line A—A of Figure 1.

Fig. 3 is a section similar to Fig. 2, the

shafts having been turned through an angle 55 of 90°.

Fig. 4 is a plan view of the device, the casing being shown in section.

Figs. 5 and 6 illustrate a modified construction with means for regulating the 60 amount of fluid passing, and means for effecting reversal of the rotation when the device is used as an engine.

In the annular casing 1, which serves for controlling the inlet and outlet ports, are 65 journaled shafts 2 and 3 positioned at an angle to one another and connected firmly to, or integral with, spherical sectors 4 and 5. The apices of these sectors are pivoted to an intermediate disc 6, so that the latter, 70 as soon as the spherical sectors rotate, partakes of this rotation, and also oscillates with respect to the faces of these sectors, whereby between the disc 6 and the sectors, inlet and outlet spaces for the forcing or delivery 75 fluid are created. The intermediate disc 6 carries spherical shells 7 and 7', the walls of which, contrary to the known device according to the U. S. Patent No. 1,150,430, are materially thickened, particularly 80 increasing towards the intermediate disc in such a way that the inner walls of the spherical shells are, for example, formed by plane faces, which run parallel to the shafts 2 and 3 respectively. Correspondingly, the spherical sectors 4 and 5 are reduced to wedges the breadth of which transversely to the axis does not exceed, or only slightly exceeds, the width of the slots 9 and 10. These 85 wedges are embraced by the spherical shells 90 7 and 7', which form part of the disc 6 or supplement the disc 6 to constitute a full sphere with the exception of the slots 9 and 10. The wedges 4 and 5 are connected with the shafts 2 and 3 through the slots 9 and 10 95 and are shouldered at 11 and 12 to exactly fit the slots 9 and 10. The feeding and discharging of the driving and forcing means is effected by pipes 13 and 14 respectively.

The regulation and reversal can be effected 100 by means shown in Figs. 5 and 6, in a known manner, by bodily displacing the shafts 2 and 3 relatively to one another, whereby the slot permitting the displacement of the shaft 3, is closed up or made tight, preferably 105 by means of a suitable ring 15, which moves together with the shaft 3.

I claim:—

A pump, comprising, a rotary and oscillatory piston formed by an intermediate disc fixed to a hollow sphere, inlet and outlet slots in the sphere, two rotatable spherical sectors forming part of the hollow sphere and pivoted to the intermediate disc in positions inclined to each other by means of a universal joint, the spherical sectors being

in the shape of wedges the breadth of each of which at most only slightly exceeds the width of the slots.

In testimony whereof I have signed my name to this specification.

HANS ALBERT FRIEDRICH
LEOPOLD MAX WARSCHAU.
